Attorney.

UNITED STATES PATENT OFFICE.

JOHN JUNGERS, OF GRAFTON, WISCONSIN.

DESIGN FOR A RANGE.

50,789.

Specification for Design.

Patented May 15, 1917.

Application filed January 11, 1917. Serial No. 141,900. Term of patent 14 years.

To all whom it may concern:

Be it known that I, JOHN JUNGERS, a citizen of the United States, residing at Grafton, in the county of Ozaukee and State of Wisconsin, have invented a new, original, and ornamental Design for Ranges, of which the following is a specification, reference being had to the accompanying drawing, forming a part thereof.

The figure is a perspective view of a range showing my new design.

I claim:

The ornamental design for a range as shown.

JOHN JUNGERS.

Witnesses:

ROBT. P. ZAUN,
LOUIS ZAUN.
